[57] **CLAIM**

The ornamental design for tool for cleaning a gas grill burner or the like, substantially as shown and described.

DESCRIPTION

FIG. 1 is a left side elevational view of the tool for cleaning a gas grill burner or the like showing my new design;

FIG. 2 is a front elevational view thereof;

FIG. 3 is a right side elevational view thereof; and

FIG. 4 is a top plan view thereof, the bottom plan being identical thereto.

FIG 1

FIG 2

FIG 3

FIG 4
